UNITED STATES PATENT OFFICE

ROBERT B. VAN DYKE, OF ANDERSON, INDIANA, ASSIGNOR TO ALFRED R. BONE, OF SAME PLACE.

SPRINKLER.

SPECIFICATION forming part of Letters Patent No. 530,464, dated December 4, 1894.

Application filed October 9, 1893. Serial No. 487,659. (No model.)

To all whom it may concern:

Be it known that I, ROBERT B. VAN DYKE, a citizen of the United States, residing at Anderson, in the county of Madison and State of

5 Indiana, have invented certain new and useful Improvements in Sprinklers, of which the following is a specification, reference being had therein to the accompanying drawings.

My invention relates to a device for sprinkling grass, flowers, and the like, and the object of my invention is to provide a sprinkler having a stationary tubular portion adapted for connection with a suitable water-supply, and a nozzle, or spraying device, connected therewith by means of a comparatively short section of flexible tubing, whereby the pressure of the water in passing through the flexible tube will cause said tube, and with it the nozzle, to vibrate, more or less rapidly, in an eccentric and irregular manner, thus producing a novel and pleasing effect and insuring a thorough sprinkling of the surrounding grass.

A further object of my invention is to provide a sprinkler having a stationary tubular portion adapted for connection with a suitable water-supply, and a spraying device connected thereto by means of a flexible tube of less diameter than said stationary portion.

30 A further object is to provide a suitable coupling between the stationary and flexible tubes.

In the drawings:—Figure 1 is a view of my improved sprinkler attached to a water-plug, and Fig. 2 is a vertical section of the stationary portion.

40 A indicates the stationary portion, comprising a lower section, B, of hose-pipe of the ordinary construction, having at its free end the usual screw-cap, b, for attaching it to a water-plug, and an upper section, B', of metal, having an enlarged portion, b', internally screw-threaded, and a reduced portion, b''. The tube B' is connected with the tube, B, by means of an externally threaded tube, b³, which screws into the lower and upper ends of each, respectively.

C indicates a flexible tube, which is of less diameter than the tube, B, and which at one 45 end is connected with the upper reduced end of the tube, B', and at its other is provided

with a spraying device, D, which may be of any well-known construction, although the form shown in the drawings has been found to be desirable.

55

In practice, the tube C may be from a foot to a foot-and-a-half in length and about one-half an inch in diameter, my entire device being about two and one-half feet long; but these dimensions may be changed, and the 60 tube made shorter and smaller or longer and larger, according as the pressure of the water is small or great.

In operation, the device is attached to an ordinary garden-hose plug, and the water 65 turned on. The pipe, C, being comparatively small, offers great resistance to the passage through it of the water, and being very flexible, it is thereby caused to vibrate or wriggle in an eccentric and irregular manner, throwing 70 the water in all directions.

While I have shown and claimed the stationary portion of my device as being made in two parts, it is evident that it could be formed in one piece, and such modification is 75 within the spirit of my invention.

My device is also not limited in operation to sprinkling grass, but may be used in connection with a fountain.

Having thus described my invention, what 80 I claim as new, and desire to secure by Letters Patent, is—

A sprinkler comprising a lower resilient section, a screw-threaded coupling secured to the lower end thereof, and exteriorly threaded 85 tube secured at its lower end, in the upper end of said resilient section, an upper rigid section of smaller diameter than said lower section having a lower enlarged end, which latter is provided with an interior screw-thread 90 for engagement with the upper projecting end of said externally threaded tube, a flexible tube secured to the upper end of said rigid section, and a nozzle on the free end of said flexible tube, substantially as and for the 95 purpose set forth.

In testimony whereof I hereto affix my signature in presence of two witnesses.

ROBERT B. VAN DYKE.
